UNITED STATES PATENT OFFICE.

JAMES SCHORNACK, OF BELLEVILLE, NEW JERSEY.

DOORCHECK.

Application filed December 10, 1927. Serial No. 239,197.

My invention relates to improvements in door checks.

In accordance with my invention, I provide a door check embodying a shock absorbing device which is carried by the door frame, and a connecting or coupling device carried by the door. Means are provided whereby the engagement between the coupling device and the shock absorbing device, 10 is automatically broken, when the door has been moved outwardly to a selected position, thus rendering the door free for convenient and easy movement, throughout the remainder or major portion of its opening or closing movement. The device is extremely simple in construction, cheap to manufacture and reliable in operation.

In the accompanying drawings, forming a part of this specification, and in which like numerals are employed to designate like parts throughout the same,

Figure 1 is a side elevation of a door stop embodying my invention,

Figure 2 is a plan view of the same,

Figure 3 is a transverse section taken on line 3—3 of Figure 1, and,

Figure 4 is a perspective view of the connecting or coupling device.

In the drawings, wherein for the purpose of illustration is shown a preferred embodiment of my invention, the numeral 5 designates the top of the door frame or jamb and 6 a horizontally swinging door.

The door check embodies a shock absorbing device including a horizontally arranged cylinder 7, extending transversely of the door jamb, and provided at its top with apertured arms or brackets 8, for attachment to the door jamb, through the medium 40 of screws 9, or the like. The cylinder 7 has a plunger 10 mounted to slide therein, and having a substantially air-tight fit with the same. This plunger is connected with a rod 11, slideable within a bearing 12, and having a loose fit therein, so that air may readily pass into the cylinder 7, about the rod 11. The cylinder 7 is provided near its rear end with a contracted opening 13, which permits of the retarded entrance and escape of the 50 air to and from the cylinder 7, upon the rear side of the plunger 10. The plunger rod 11 is provided at its forward end with a head 14, rigidly secured thereto. The forward face of this head is tapered or inclined and the 55 head has a straight rear shoulder 15.

The connecting or coupling device is car-

ried by the door 6 and embodies a plate or leaf 16, ordinarily horizontally arranged, and this leaf or plate is equipped with knuckles 17, for co-action with a knuckle 18, formed upon a vertical leaf 19, which is rigidly attached to the door 6, by screws 20, or the like. The knuckles 17 and 18 are pivotally held together by means of a pivot element, which may be in the form of a 60 cotter-pin 21. This cotter-pin is adapted for connection with a spring, which may be employed to close the door. The plate 16 can not drop below the horizontal position, since it is equipped with a stop 16', rigidly 65 attached thereto, and adapted to engage with a leaf 19. Preferably formed integral with the plate 16 is a substantially vertical depending engaging tongue 22, adapted for co-action with the head 14, in a manner to be described. Also preferably formed integral with the plate 16 is a releasing arm 23, which is normally horizontally arranged and provided at its free end with a depending trip extension or cam 24. The trip extension 24 70 is adapted to be brought into engagement with a stationary trip 25, arranged in the path of travel of the same, and the trip 25 is rigidly attached to the cylinder 7.

The operation of the device is as follows: 85

When the door 6 is moved toward the closed position, the engaging tongue or element 22 is brought into engagement with the forward tapered face of the head 14, and will ride over the same, and the tongue 22 90 will then drop behind the shoulder 15. The head 14 will now engage the leaf 19, and the continued closing movement of the door 6 will shift the plunger 10 rearwardly, and the movement of this plunger is opposed by 95 the gradually escaping air through the port or opening 13. The action of the plunger will, therefore, prevent the sudden closing or slamming of the door. When the door is partly opened, the tongue 22 will engage 100 behind the shoulder 15, and the plunger 10 is now moved forwardly, but in a retarded manner, as the air must enter the cylinder through the contracted opening 13. When the door has been opened for a short distance, the trip or cam 24 will ride upon the trip 25, swinging plate 16 upwardly, which raises the engaging tongue or element 23 so that it will clear the shoulder 15. The further opening movement of the door causes a 105 disengagement between the tongue 22 and the head 14, whereby the opening movement 110

of the door may be completed without the action of the plunger 10 and associated elements. The plunger 10 has thus been shifted to the forward position, before being disconnected from the door, and will, therefore, have its head 14 in the upper forward position, for engagement with the door, before it is completely closed, whereby slamming of the door is prevented.

10 It is to be understood that the form of my invention, herewith shown and described, is to be taken as a preferred example of the same, and that various changes in the shape, size and arrangement of parts may be resorted to without departing from the spirit of my invention, or the scope of the subjoined claims.

Having thus described my invention, I claim:

20 1. In a door check, a cylinder adapted to be secured to the door jamb and having a restricted opening, a plunger to slide in the cylinder, a plunger rod attached to the

plunger, a head carried by a plunger rod and provided with a forward inclined face and 25 a rear shoulder, a plate hinged to the door to swing vertically and provided with a depending engaging lip for co-action with said head, a releasing arm connected with the plate and having a cam, and a stationary 30 trip arranged in the path of travel of the cam.

2. In a door check, a cylinder, a plunger to slide within the cylinder, a plunger rod attached to the plunger, a head secured to the forward end of the plunger rod, a member arranged for detachable engagement with the head, a pivoted releasing arm permanently connected with the member and adapted to shift it out of engagement with 35 said head, and trip means to swing the releasing arm upon its pivot when it has been shifted longitudinally a selected distance.

In testimony whereof I affix my signature.

JAMES SCHORNACK.
